UNITED STATES PATENT OFFICE

JOTT GRANT, OF BOSTON, MASSACHUSETTS.

NAPKIN-HOLDER.

SPECIFICATION forming part of Letters Patent No. 368,944, dated August 30, 1887.

Application filed November 29, 1886. Serial No. 220,221. (No model.)

To all whom it may concern:

Be it known that I, JOTT GRANT, of Boston, in the county of Suffolk and State of Massachusetts, have invented a new and useful Improvement in Napkin-Holders, of which the following, taken in connection with the accompanying drawings, is a specification.

The object of my invention is to produce a napkin-holder that may serve as a device for attaching the napkin to the person of the user, as a spreader for the napkin, and as a holder for it when rolled up and not in use. This object I obtain by the mechanism shown in the accompanying drawings, in which—

1; Figure 1 is a perspective view showing the holder with a napkin attached. Fig. 2 shows, in perspective, a holder only; and Fig. 3 shows the napkin rolled up and held by the holder.

The holder itself is shown at Fig. 2 detached.

20 This holder consists of a curved piece of thin metallic plate, C, curved as shown. This metallic plate may be engraved or otherwise ornamented to suit the taste, and may have the name or monogram of the owner inscribed on it. One end of the plate C is formed into a tube, C', which clasps the loop A², formed in the wire A A'. The wire A A' A' is bent as shown at B, B', and B², Fig. 2, so as to form two clasping places, as indicated at D D', Fig.

25 2. The wire part above described serves as a holder and spreader for the napkin when the napkin is in use, as shown in Fig. 1. It also assists in holding the napkin in place when

rolled up, as shown in Fig. 3. The plate C is bent so as to form a hook at C², Fig. 2. This 35 hook serves to attach the napkin to the neck of the user when in use, and to assist in holding it together when rolled up, as shown in Fig. 3.

From the above it will be seen that my device consists of two distinct parts, although the two parts coact; but in this coaction two useful results are attained—that is, first, the device is used to spread out the napkin and to attach it to the person, as shown in Fig. 1; 45 second, the device is used to firmly hold in a compact form the napkin when rolled up and not in use. To effect this double use I have made the hook part C broad and curved, as shown, so as to form more than half of the arc 50 of a circle, and have hinged this part to the clasping spreader.

What I claim is—

In a napkin-holder, the combination of the curved plate C, said plate to be curved at one 55 end to form the hook and holder C² and formed at the other end into a quill, C', with the clasping wire spreader A A' A² B B' B², forming a lower bar, B², clasping-points at D D', and a loop at A², whereby it is held to the quill C', 60 all substantially as described, and for the purposes set forth.

JOTT GRANT.
